CLAIM

The ornamental design for a table top cooking grill, as shown.

DESCRIPTION

FIG. 1 is a perspective view of a first embodiment of a table top cooking grill taken obliquely from above;

FIG. 2 is a further perspective view thereof, taken obliquely from below;

FIG. 3 is a side elevational view thereof, the opposite side being a mirror image; and

FIG. 4 is an end elevational view thereof, the opposite end being a mirror image.

FIG. 1

FIG. 2

FIG. 4
